UNITED STATES PATENT OFFICE.

MAGULER BUTLER, OF ROCHESTER, NEW YORK.

DESIGN FOR A BICYCLE-TIRE CLEANER.

SPECIFICATION forming part of Design No. 26,521, dated January 12, 1897.

Application filed December 3, 1896. Serial No. 614,368. Term of patent 3½ years.

To all whom it may concern:

Be it known that I, MAGULER BUTLER, a citizen of the United States, and a resident of the city of Rochester, county of Monroe and State of New York, have invented and produced a new and useful Design for Bicycle-Tire Cleaners, of which the following is a specification, reference being had to the accompanying drawings, in which—

10 Figure 1 is an elevation of a device embodying my invention, and Fig. 2 is a top plan thereof.

15 The handle has an elongated ovoid portion A, flaring as at a, and having a bead a'. Thence it continues in the cylindrical portion

a² and is surmounted by the curved plate B, which is narrow and is transversely set upon the end of the cylindrical portion a², and has the rounded flaring ends b'. The inner or concave portion of the plate B is provided with 20 a longitudinally-corrugated facing C. The corrugations c are shown in Fig. 2.

What I claim is—

The design for a bicycle-tire cleaner, substantially as shown and described.

MAGULER BUTLER.
